UNITED STATES PATENT OFFICE.

CHARLES M. RANKERT, OF SPOKANE, WASHINGTON.

TOY.

1,268,998.

Specification of Letters Patent. Patented June 11, 1918.

Application filed October 22, 1917. Serial No. 197,878.

To all whom it may concern:

Be it known that I, CHARLES M. RANKERT, a citizen of the United States, residing at Spokane, in the county of Spokane, State of Washington, have invented new and useful Improvements in Toys, of which the following is a specification.

This invention relates to improvements in toys.

- 10 My invention includes a supporting member or spindle which is provided with a series of projections linearly disposed along the length of the spindle, a body being rotatively mounted on one end of the spindle.
- 15 The remaining end of the spindle is adapted to be held in the hand of the player and a vibratory generating member is adapted to be held in the remaining hand of the player and rapidly reciprocated along said series of 20 projections. The result of such rapid vibration generated to the spindle is to impart to the free end of the latter an orbital movement such as will transmit to the rotative body a sufficient thrust to cause the latter 25 to rotate.

One of the novel features of my invention consists in mounting the rotative body on one end of the spindle in offset or eccentric relation with respect to the longitudinal axis 30 of the spindle. Thus the orbital movement of the spindle will always rotate said body in one direction, unless the offset side of the spindle is supported by the thumb or finger of the player, in which event the 35 body will reverse its direction of rotation.

My invention will be more fully described in connection with the accompanying drawing and will be more particularly pointed out in and by the appended claims.

40 In the drawing:

Figure 1 is a plan view of a toy embodying my improved invention and in which the free end of the spindle is adapted to be held in the left hand of the player and the longer end of the actuating member by 45 the other hand of the player. Fig. 2 is an end view showing the eccentric mounting of the member on the spindle.

Fig. 3, is an enlarged view showing the 50 series of linear projections on the spindle over which the member is adapted to be reciprocated.

Like characters of reference designate 55 similar parts throughout the different figures of the drawing.

As illustrated, 1 designates a spindle or

carrier on which is disposed a series of linearly arranged projections 2. The end 3 of said spindle is adapted to be firmly held in one hand of the player. At the opposite 60 end of said spindle, as designated at 4, is a rotatively mounted body 5 which may consist of an elongated strip of material of any desired form. This body 5 is mounted upon a pin 6 which projects into the spindle 1, 65 as shown, somewhat offset or eccentric with respect to the longitudinal axis of the spindle 1. A head 7 on the pin 6 serves to retain the body 5 thereon.

An actuating member is shown which is 70 preferably in the form of a rod 8 and this rod 8 is adapted to be held by the remaining hand of the operator or player and reciprocated rapidly along the projections 2. It is highly desirable to have the projections 75 2 equidistantly spaced. As the member 8 is rapidly reciprocated in pressure contact with the projections 2, gyratory and vibratory orbital movement is imparted to the free end 4 and this results in imparting a 80 rotative thrust to the body 5 which will rotate said body in a counter clock-wise direction, looking from the right of Fig. 1. If the thumb 9 of the player is held in pressure sliding engagement along the off- 85 set side 10 of the spindle 1 then the orbital movement of the free end 4 is reversed and this results in reversing the direction of rotation of the body 5.

It is believed the advantages and utilities 90 of my invention will be fully understood from the foregoing description, and while I have herein shown and described one specific form of my invention I do not wish to be limited thereto, except for such limitations as the claims may import.

I claim;

1. In a toy, a rotating body, a spindle supporting said body and having a series of projections extending substantially transversely with respect to the longitudinal axis of said spindle, a member adapted to be reciprocated along said projections to vibrate the latter, said body being rotatable about an axis eccentric to the longitudinal axis of 105 said spindle whereby brace of the latter by the finger will generate rotative thrust to rotate said body, substantially as described.

2. In a toy, a spindle adapted to be held in one hand of the player and having a 110 roughened linear surface, a body rotatively mounted on one end of said spindle, a

member adapted to be held by the other hand of the player and reciprocated along said roughened surface to generate vibratory orbital movement of the free end of said spindle, said body being mounted to rotate about an axis off center with respect to the axis of said spindle whereby said orbital movement of said spindle will cause said body to rotate in a direction corre-

sponding to the direction of said body and whereby support of the spindle by the thumb finger of the player on the side of the spindle will cause said body to reverse its direction of rotation, substantially as described.

In testimony, that I claim the foregoing 15 as my own, I hereby affix my signature.

CHARLES M. RANKERT.
